EYEGLASS DISPLAY UNIT

Richard S. Dunchock, Northville, Mich., assignor to
Optarac Corporation, Hollywood, Fla.

Filed Aug. 19, 1974, Ser. No. 498,542

Term of patent 14 years

Int. Cl. D20—02

U.S. Cl. D6—85

FIG. 1 is a perspective view illustrating an eyeglass display unit showing my new design;

FIG. 2 is a front elevational view thereof;

FIG. 3 is a right-end elevational view thereof;

FIG. 4 is a rear elevational view thereof;

FIG. 5 is a left-end elevational view thereof;

FIG. 6 is a top elevational view thereof; and

FIG. 7 is a bottom elevational view thereof.

I claim:

The ornamental design for an eyeglass display unit, as shown.
